(57) **CLAIM**

The ornamental design for a swaddle, as shown and described.

DESCRIPTION

FIG. 1 is a perspective view of a swaddle showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof;

FIG. 8 is a front view shown in a first configuration in use;

FIG. 9 is a front view shown in a second configuration in use;

FIG. 10 is a front view shown in a third configuration, wherein the four ends are turned outside in; and,

FIG. 11 is a front view shown in the third configuration in use.

The broken lines showing the baby in FIGS. 8-9 and 11 are for the purpose of illustrating the environmental structure and form no part of the claimed design.

1 Claim, 11 Drawing Sheets
